GRID PRINTER

John F. Brinster and Erwin Donath, Princeton, N. J., assignors to Applied Science Corporation of Princeton, Princeton, N. J., a corporation of New Jersey

Application December 9, 1953, Serial No. 397,222

6 Claims. (Cl. 346—107)

This application is a continuation-in-part of our co-pending application for "Plotter," Serial No. 377,092, filed August 28, 1953.

In said prior application means are disclosed for rapidly reproducing a graphical record of variable data in a modified form incorporating desired corrections to the data. The apparatus shown and described therein comprises photo-electric means for repeatedly scanning a graph of unmodified data at closely spaced locations therealong to obtain measures of the effective ordinates of the points at said locations, together with means for automatically deriving from a calibration curve modified data values respectively corresponding thereto, and a photographic plotter for plotting the modified data.

The present application discloses additional means for printing a rectangular co-ordinate grid to serve as a reference in establishing the co-ordinates of points on a graph produced by said plotter. The printing of this grid is caused to proceed in synchronism with the plotting of the graph and the positions of the lines comprised thereby are derived directly from the sources which determine the co-ordinates of points on the graph. Thus, the positions of the lines of constant abscissa value in the grid are derived from the positions of uniformly spaced marker lines recorded along the axis of abscissae (the time axis) of the input or unmodified data graph at the time the data are recorded, while the positions of the lines of constant ordinate value are based on the positions of similar lines of constant value (lines of constant corrected data value) displayed in conjunction with the calibration curve. This direct derivation of the positions of the grid lines from the sources determining the co-ordinates of the plotted data, makes the relationship of the grid to the plotted output graph independent of such otherwise distorting factors as slippage and change of speed of the film and paper drives and more particularly of shrinkage and other distortion of the sensitized films and paper on which the data and corrections thereto are displayed, such distortions occurring especially in the process of photographically developing these records.

It is, accordingly, an object of the invention to provide, in connection with means for plotting a graph, other means for printing a co-ordinate grid to serve as a reference for said graph, said grid comprising lines of constant co-ordinate value whose positions are derived directly from the sources determining the co-ordinates of the points on said graph.

It is another object to provide means for transferring a selected reference, or a derivative thereof, from an original graphical record to a reproduction of said record, in substantially unchanged relationship to the record.

It is a further object to provide a method of and means for recording a composite reference marking for a graphical record, operable during the plotting of said record.

Other objects and advantages of the invention will be apparent upon consideration of the following specification taken in conjunction with the appended drawings in which:

2

Fig. 1 is a combined perspective drawing and circuit diagram illustrating one embodiment of the invention;

Fig. 2 is an enlarged view of a film bearing multi-channel data graphs together with timing lines therefor;

Fig. 3 is a graph showing the time relationship of a pair of spaced electrical impulses appearing in the system;

Fig. 4 is a front elevation of a light mask appearing in Fig. 1, showing the projection of a calibration curve and reference lines thereon;

Fig. 5 is an enlarged view of a portion of a plotted graph of corrected data, together with a co-ordinate grid therefor;

Fig. 6 is a circuit diagram for a flash lamp;

Fig. 7 is an end elevation of a detail of the recording apparatus of the invention; and

Fig. 8 shows a portion of a film bearing a calibration graph, together with lines of constant co-ordinate value.

The figures in the present application correspond, respectively, to similarly numbered figures in application Serial No. 377,092, with additions showing the means of the present invention. Like reference numerals in the two applications refer to like parts and primed numerals in the present application refer to slightly modified parts.

Referring, now, to Fig. 1 input data film 51', corresponding to film 51 of the prior application, bears along one edge thereof a series of spaced parallel opaque marker lines 201 which are recorded at the time of recording the data. The axis along which these lines lie and along

which film 51' is displaced at a constant rate by motor 42 is a time axis and the lines serve as time references for the recorded data. Lines 201 are scanned, during traverse of film 51', by lamp 203, an optical system illustrated as lens 205, mask 207 and photo-tube 209. Lamp 203

35 may be shielded by shield 211 to prevent light therefrom interfering with the scanning of adjacent data channel traces by flying spot 69. Mask 207 comprises a narrow transparent trace or slit 213 which accommodates the image of one of lines 201, only, as formed thereat by

40 lens 205, and is closely adjacent photo-tube 209, the mask being displaced from its true location in the drawing for clarity of illustration. Due, therefore, to the modulation of the light reaching said tube as a result of the scanning of lines 201, a sequence of impulses (con-

45 sidered negative impulses herein) is developed in the output of the tube corresponding, respectively, to the passage of lines 201 through scanning position. By adjustment of the positions of the described scanning members, the scanning position defined by the registration of the

50 image of a marker 201 line with slit 213 can be caused to coincide with the longitudinal position along film 51' of the line of scan of flying spot 69.

The output of photo-tube 209 is passed by way of amplifier 215 to scaling circuit 217. Scaling circuits are

55 known which produce one output impulse responsive to a selected integral number of input impulses, so-called scale-of-two and scale-of-ten circuits being examples thereof. Circuit 217 on its output side is connected to the "on" lead of gate control 219 (similar to gate control 105) in control of gate 221 (similar to gate 103).

60 A control magnet 223, in addition to magnets 127, 129, is adjustably mounted on support 126 along arcuate slot 225 therein, for the development of an impulse upon the passage of permanent magnet 125 thereby. This impulse

65 passes to flashing electrode 140 of flash lamp 137 by way of lead 227, gate 221 (when open), lead 228, mixing circuit 229 and step-up transformer 152. Circuit 229 is of a type adapted to supply an output responsive to an input from either of two sources, without interaction

70 between the sources. For example, see Fig. 12 of our co-pending application Serial No. 397,189, filed December 9, 1953.

Generally opaque calibration film 119', corresponding to film 119, bears a number of transparent linear traces, narrower than trace 121, as trace 231 (Fig. 8), which are lines of constant corrected value of the data and which are superimposed on calibration curve 121 and co-extensive therewith in the direction of the axis of uncorrected values thereof. Spaced from the curve and co-extensive therewith in the direction of the axis of corrected values is a transparent area of the film constituting a slit 235 the width of whose image projected by lens 155 on mask 141 is somewhat greater than that of slit 143 in mask 141. Magnet 223 is so positioned that the impulse developed upon passage of permanent magnet 125 thereby, occurs when slit 143 lies within the lateral limits of this image of slit 235. The flashing of lamp 137 at such time causes the illuminated image of slit 235 to serve as a light source for printing a line, defined by slit 143, on paper 147, for example, line 241 (Fig. 5).

In operation, as film 51' is displaced by drive 31 at a substantially constant rate, lines 201 are scanned longitudinally of the film at the same time that the recorded data and reference traces, as traces 55, 53, are repeatedly scanned laterally thereof by flying spot 69 with continuous displacement of the line of scan longitudinally of the film, at a constant rate. The scanning rate of the former scan is much lower than that of the latter scan. The rate of occurrence of impulses in the output of photo-tube 209 resulting from the scanning of lines 201 is reduced, by a selected factor, in the output of scaling circuit 217.

An impulse appearing in the output of circuit 217 responsive to a sequence of impulses applied to the input thereof, passes to the "on" lead of gate control 219 causing the opening of gate 221. Upon passage of permanent magnet 125 past control magnet 223, the impulse thereby developed passes through gate 221 to the "off" lead of gate control 219 and closes the gate. The impulse in the output of gate 221 also passes through mixing circuit 229, and after being intensified by step-up transformer 152, is applied to flashing electrode 140 of lamp 137. The resulting substantially instantaneous flash prints a line, defined by slit 143, on recording paper 147, to supply a timing line, or line of constant abscissa value, on the output record, as line 241 (Fig. 5). The transference of this line from the input record along with the transfer of the abscissa values of the plotted points of output graph 161 insures that the relationship along the time axis of reference lines and plotted points is independent of distortions of film or recording paper and of slippage and changes of speed in the various drives and, since lines 201 were recorded along with the original recording of the data, their counterparts on the out-put record are true time references for the interpretation of the corrected data.

As described in application Serial No. 377,092, the ordinates of the points of output graph 161 are determined by the positions of successive intersections of the projected image 121' of calibration graph 121 and slit 143 in mask 141, measured along the axis of corrected values of the graph upon the completion of displacements along the axis of uncorrected values thereof respectively proportional to the input data.

In the operation of the means of the present invention, as each ordinate is thus determined and a point on the output graph printed, other points, defined by the intersections of the projections on mask 141 of all of transparent linear traces 231 with slit 143, are simultaneously printed. Since traces 231 are lines of constant corrected data value displayed in conjunction with and in fixed relationship to calibration graph 121, the repeated printing of these last-named points of intersection simultaneously with the successive printing of the data points, results in narrow, relatively faint lines of constant ordinate value constituted by the repeatedly printed points, being recorded along with graph 161, as line 241 (Fig. 5). The positions of these lines are directly derived from the source with

respect to which the ordinate values of points on the output graph are determined and hence have a relationship to said points unaffected by distortions of paper or film or by driving speed changes.

5 In summary, input film 51' and calibration film 119', displaying graphical records of variable data, are each provided with reference markings for establishing co-ordinate values along one axis thereof. In the case of the former record this axis is a time axis, in the latter, 10 the axis of corrected values of the data. Along their other axes, the input record graph, as uncorrected data graph 53, and the calibration curve 121 have like co-ordinate values, as to corresponding points thereon, each axis being an axis of uncorrected values of the data. The 15 output record, graph 161, shows the relationship of corrected values of the data and time. The co-ordinates of the points thereon are determined by the positions along the axis of corrected values and of time, respectively, of corresponding points (points of like uncorrected data 20 value) on the input record and calibration curve. The output record, in addition, comprises a grid of constant co-ordinate lines whose positions, along each axis, relative to the points on the output graphs, are determined by the positions of the marker lines along the corresponding axes of the input records and calibration curve, respectively.

While means have been described thereby the rectangular co-ordinates along one axis of points on an automatically plotted graph and the positions of reference 30 markings therefor are derived from one source and co-ordinates of said points along the other axis together with the positions of reference markings therefor are derived from another source, the invention also contemplates the printing of a reference grid having elements whose 35 positions are respectively derived from those of like elements of a grid displayed in conjunction with a single data source.

The embodiment of the invention shown herein is by way of illustration only, the limits of the invention being 40 defined solely in the appended claims.

We claim:

1. In plotting apparatus, means displaying first and second graphical records of variable data each having reference markings spaced along one axis thereof, mutually 45 corresponding points on said two records having like co-ordinate values along the other axes thereof, a plotter adapted simultaneously to plot a third graph and print a reference grid therefor comprising a series of lines of constant co-ordinate value along each axis thereof, means determining the co-ordinates of a plotted point on said third graph in accordance with the respective positions along said axes having reference markings therealong of a pair of corresponding points on said two records, and means likewise determining the positions of the lines of the two series thereof constituting said grid in accordance with the positions of said reference markings along said last named axes, respectively.

2. Apparatus as claimed in claim 1 wherein said plotter includes projective photographic printing means actuated by a flash lamp together with a sensitized base and a member bearing a slit continuously displaceable relative to said lamp, illumination of said slit by said lamp printing a line of said grid, and said means determining the positions of the grid lines includes means for scanning said reference markings along the axis thereof and controlling the flashing of said lamp in accordance with the positions thereof along said axis.

3. Apparatus as claimed in claim 1 wherein said plotter includes projective photographic printing means actuated by a flash lamp for plotting said third graph and printing said grid lines, said printing means including means whereby said lines along one axis are sequentially printed in their entirety by single flashes of said lamp and said lines along the other axis are simultaneously printed point-by-point by repeat flashes of said lamp in synchron-

nism with the printing of the points on said third graph.

4. In plotting apparatus means for transferring a time reference from a graphical record of unmodified data to a similar record of modified data in undisturbed relationship to corresponding points on said two records comprising means displaying a graphical record of unmodified data having a data axis and a time axis and including reference markings spaced along the latter axis, means for continuously scanning across said markings at a constant rate to produce a sequence of uniformly spaced electrical impulses respectively corresponding thereto, means for repeatedly scanning across said record of unmodified data values transversely of said time axis with progressive displacement of successive positions of the line of scan at a constant rate along said time axis to produce a sequence of electrical signals respectively proportional to successive values of the data along said record, said data signals thereby having an established time relationship to said reference marking impulses, means for individually modifying the values of said signals in pre-established manner without disturbing said relationship, a plotter for producing a graphical record of said modified data having a second data axis and a second time axis together with reference markings along said latter axis, said plotter including a base for displaying said record and means for displacing said base at a constant rate along said second time axis together with means for sub-

20 25

stantially instantaneously recording indicia on said moving base, and means for controlling said last means to cause the plotting of a data point on said record positioned along said second time axis in accordance with the occurrence of one of said modified signals and for controlling the printing of a reference marking positioned along said second time axis in accordance with the occurrence of one of said reference marking impulses.

5. Apparatus as claimed in claim 4 wherein said displaceable base is photo-sensitive and said means for recording indicia thereon includes a flash lamp controlled in accordance with said data signals and reference marking impulses, respectively.

6. Apparatus as claimed in claim 4 wherein the data signals developed by scanning said unmodified data record are pulse position signals proportional to the spacing of a point on the record and an established reference therefor along the line of scan.
